Wes. 1765

Eleazar Ney of Lowell Mass.
Assign to
The Lowell Manufacturing Company
Letters Patent No 1765, dated June 16, 1865.

The schedule referred to in these Letters Patent and making part of the same.

To all whom it may concern:

Be it known, that I, Eleazar J. Ney, of Lowell, in the County of Middlesex and State of Massachusetts, have originated and designed a new pattern for carpets or other fabrics of which the following is a full, clear and exact description, reference being had to the accompanying drawings making part of this specification.

Incomes 1 and 2. are fourths of oblong blocks, resting on the large dotted figures 3, 4. which are surrounded by a narrow band. A. is one half of an irregular figure resting on the large set figure B. which is surrounded by a narrow band.

Lying between the figures B. and 3, 4. respectively, are the small set figures 5, 6. and they are connected with figures B. 3 and 4. by means of curved lines.

C. is one half of a set figure, composed of four leaves resting on the mottled ground 7. which has an irregular edge. Incomes D and E. are fourths of set figures resting on mottled ground. The remaining parts of the design are the bands 8, 9, 10, 11. which are composed of small lines.

The colors employed for the different portions of the design may be varied to suit the taste and wish of the manufacturer.

Claim

What I claim as my invention, and desire to secure by letters patent, is the design or pattern for carpets or other fabrics, herein set forth.
